A. T. HOLDER

THEFT PREVENTIVE DEVICE

Filed Oct. 11, 1920

A. T. Holder

By Watson E. Coleman
Attorney

UNITED STATES PATENT OFFICE.

ANDREW T. HOLDER, OF SAN FRANCISCO, CALIFORNIA.

THEFT-PREVENTIVE DEVICE.

Application filed October 11, 1920. Serial No. 416,179.

To all whom it may concern:

Be it known that I, ANDREW T. HOLDER, a citizen of the United States, residing at San Francisco, in the county of San Francisco and State of California, have invented certain new and useful Improvements in Theft-Preventive Devices, of which the following is a specification, reference being had to the accompanying drawings.

10 This invention relates to theft preventive devices and has relation more particularly to a device of this general character especially designed and adapted for use in connection with motor driven vehicles and the like, and it is an object of the invention to provide a novel and improved device of this general character embodying a member carried by the vehicle and adapted to be adjusted or moved into a position to engage a 15 roadway or other surface upon which the vehicle is arranged in a manner to hold said vehicle against travel in one direction and preferably forwardly.

Another object of the invention is to provide a locking member or bar supported by the vehicle for swinging movement in a vertical direction and which member or bar, when in one position, engages the roadway or other surface to hold the vehicle against 20 forward travel, together with means for moving the member or bar into working or operative position and holding the same in such position.

An additional object of the invention is to 25 provide a novel and improved device of this general character including a member or bar supported by the vehicle for swinging movement in a vertical direction, together with manually operated means for swinging the member or bar downwardly into working position and wherein automatic means are provided for imparting upward swinging movement to the member or bar and to support the same in a raised or inoperative position.

The invention consists in the details of construction and in the combination and arrangement of the several parts of my improved theft preventive device whereby certain important advantages are attained and the device rendered simpler, less expensive and otherwise more convenient and advan-

tageous for use, as will be hereinafter more fully set forth.

The novel features of my invention will 55 hereinafter be definitely claimed.

In order that my invention may be the better understood, I will now proceed to describe the same with reference to the accompanying drawings, wherein:

Figure 1 is a view in side elevation illustrating a vehicle having applied thereto a theft preventive device constructed in accordance with an embodiment of my invention.

Figure 2 is an enlarged fragmentary view partly in side elevation and partly in section illustrating certain details of construction comprised in my improved device as herein embodied.

Figure 3 is a view partly in section and partly in rear elevation of the upper or pivoted end portion of the locking member or bar and the parts concomitant thereto, and

Figure 4 is a view partly in section and partly in top plan illustrating the means for manually adjusting the locking member or bar into lowered or working position and for locking the same in such position.

As disclosed in the accompanying drawings, V denotes a motor driven vehicle of a conventional type wherein the chassis or frame C thereof at a point adjacent to but in advance of the rear drive wheels W is provided with a transversely disposed beam 80 1. Depending from each of the side beams 2 of the chassis or frame C at a point in advance of the beam 1 but preferably immediately adjacent thereto is a boxing 3 which serves as a mounting for an end portion of a 85 rod 4 extending transversely of the chassis or frame C.

B denotes an elongated holding bar or member having its lower or working end portion provided with a spike or penetrating point 5. The upper or opposite end portion of the bar or member B is transversely enlarged, as at 6, and is provided with a sleeve or barrel 7 having its axis substantially perpendicular to the longitudinal axis of the bar or member B. The sleeve or barrel 7 loosely surrounds the rod 4 whereby the bar or member B is supported for swinging movement in a vertical direction.

In the present embodiment of my invention, the bar or member B is illustrated as arranged adjacent a side member 2 of the chassis or frame C although it is to be understood that the bar or member B may be located as preferred with respect to the transverse center of the chassis or frame C.

As herein disclosed, the bar or member B is automatically swung or moved upwardly 10 into an inoperative position through the medium of the retractile member 8, herein disclosed as a coil spring, having one end portion secured to a laterally directed pin 9 carried by the upper end portion of the bar or member B while the opposite end portion of the member or spring 8 is secured to an inwardly directed rod 10 carried by the adjacent side beam 2.

Extending upwardly and forwardly from 20 the sleeve or barrel 7 and at a point remote from the member or spring 8 is a rock arm 11 terminating in an eye member 12. Secured to the eye member 12 is an end portion of a flexible member 14 which extends 25 forwardly of the chassis or frame C and around a guide pulley 15 mounted as desired upon the chassis or frame C. From the pulley 15, the member 14 extends outwardly and laterally and is suitably anchored, as at 16, 30 to a chain 17. The chain 17 is directed through a suitable opening 18 provided in the body of the vehicle slightly above the forward end portion of the running board R.

Carried by the outer face of the body adjacent the opening 18 is a lock mechanism 19 including a sliding bolt 20. The bolt 20, when extended, is adapted to pass 35 through a link comprised in the chain 17 so that the member 14 will be held against retrograde movement and particularly after 40 manual strain has been imposed thereon to swing the bar or member B downwardly into working or operative position with respect to the roadway or other surface.

Upon pulling upon the exterior portion 45 of the chain 17, the member 14 will cause the bar or member B to swing downwardly into a working or operative position, as particularly illustrated in Figure 2, and the lock mechanism 19, preferably of a key type, cooperates with the chain 17 to hold 50 said bar or member B in such position. With the bar or member B in this position, attempt to move the vehicle V forwardly 55 will result in the point or spike 5 penetrating the roadway or other surface whereby forward travel of the vehicle is prevented. Under certain conditions, there may possibly be a slight forward advance of the 60 vehicle but in which event the member or bar B will swing upwardly and thereby raise the rear portion of the vehicle, resulting in one or both of the rear drive wheels W being elevated out of contact with 65 the roadway or other surface.

It is of particular importance to provide means to prevent the bar or member B passing beyond a vertical center when in its working or operative position and for which reason I employ an arm 21 suitably secured 70 to and depending from the beam 1. The lower end portion of the arm 21 is provided with a head 22 which constitutes a bumper and which coacts with the bar or member B to prevent the same passing beyond a vertical center. I find it of particular advantage to provide the forward or contacting face of the head or bumper 22 with a notch 23, preferably V-shaped in plan, and in which enters the adjacent portion of the bar or member B in the event the rear portion of the vehicle should move upwardly and forwardly.

When the chain 17 is released, the member or spring 12 will automatically throw the bar or member B upwardly into an inoperative position and maintain the same in such position so that normally the member or bar B will offer no obstruction or hindrance to the desired travel of the vehicle.

It is also to be particularly noted that my improved device, when applied to a vehicle is noiseless. It will also be understood that by having the chain 17 pass through a side portion of the vehicle, as hereinbefore described, any unauthorized person tampering with the lock mechanism 19 may be readily detected as it will be obvious that any one endeavoring to release the chain 100 17 without a key has unauthorized use of the vehicle.

From the foregoing description it is thought to be obvious that a theft preventive device constructed in accordance with my invention is particularly well adapted for use by reason of the convenience and facility with which it may be assembled and operated, and it will also be obvious that my invention is susceptible of some change 110 and modification without departing from the principles and spirit thereof and for this reason I do not wish to be understood as limiting myself to the precise arrangement and formation of the several parts herein shown in carrying out my invention in practice except as hereinafter claimed.

I claim:

The combination with a vehicle chassis, of a dog pivotally depending from and supported from the side of the chassis for swinging movement in a vertical direction, said dog when lowered extending forwardly and downwardly and provided with a sharpened nose to engage with the ground 125 to prevent forward movement of the vehicle, tensioning means for holding the dog normally elevated on its pivot, means for locking the dog in a lowered position, and an arm depending from and fixed to the 130

side of the chassis and extending forwardly and terminating in a head at its lower end positioned substantially beneath the pivot of the dog, said head constituting an abutment for the dog to prevent the dog passing beyond a vertical center, the dog engaging face of the head having a notch into which the dog at a point below its pivot en-

gages, the opposed walls of the notch acting to prevent lateral distortion of the dog, **10** when the dog is moved suddenly toward the ground.

In testimony whereof I hereunto affix my signature.

ANDREW T. HOLDER.
